UNITED STATES PATENT OFFICE.

WALLACE C. MILLS, OF ROCKFORD, ILLINOIS, ASSIGNOR TO J. L. CLARK MANUFACTURING CO., OF ROCKFORD, ILLINOIS, A CORPORATION OF ILLINOIS.

DESIGN FOR A DISPLAY REEL FOR HOLDING ELECTRIC-FIXTURE CORD.

Application filed June 27, 1928. Serial No. 27,296. Term of patent 14 years.

To all whom it may concern:

Be it known that I, WALLACE C. MILLS, a citizen of the United States, residing at Rockford, in county of Winnebago and State of Illinois, have invented a new, original, and ornamental Design for a Display Reel for Holding Electric-Fixture Cord, of which the following is a specification, reference being had to the accompanying drawing, forming part hereof.

In the drawings:

Figure 1 is a perspective view of a reel embodying my new design.

Fig. 2 is an elevational view of one end

of the reel.

The distinctive feature of the design consists in the relief of the flat surfaces of the spool ends by the combination of annular beads and ribs with flat radially disposed panels periodically interrupting the continuity of the ribs.

I claim:

The ornamental design for a display reel for holding electric fixture cord substantially as shown and described.

WALLACE C. MILLS.
